UNITED STATES PATENT OFFICE.

MINERVA ELIZABETH HALL, OF TORONTO, CANADA.

STAIR-CARPET FASTENER.

SPECIFICATION forming part of Letters Patent No. 593,212, dated November 9, 1897.

Application filed June 11, 1896. Serial No. 595,158. (No model.)

To all whom it may concern:

Be it known that I, MINERVA ELIZABETH HALL, of the city of Toronto, Province of Ontario, and Dominion of Canada, have invented 5 a new and useful Carpet-Securer, of which the following is a specification.

My invention relates to improvements in stair-carpet securers; and it consists of a se- 10 curer which may be permanently secured to the stairs and need not be removed to allow of a stair-carpet being taken up or of the same or a wider or narrower carpet being laid down. I attain these objects by the de- 15 vice illustrated in the accompanying draw- ings, in which—

Figure 1 is a top view or plan. Fig. 2 is a front view; and Fig. 3 is a section of the line J K, showing the securer secured to the stair and the carpet secured by the securer.

20 Similar letters refer to similar parts through- out the several views.

The securer is composed of steel wire or other spring material. The member B, which may be termed the "base," is intended to be 25 permanently secured to the woodwork of the chair H H by screws through the C C, and is intended to be covered by the carpet G G. The member D E A, which may be termed the "loop," consists of an arm A, extending 30 from the base to a turn or bend E, and an

arm D, returning from the bend E and ter- minated by a coil rosette or ornament.

The loop A E D forms a spring, of which the arm D is intended to press upon the sur- 35 face of the carpet G G and hold it securely in position. It is intended that the edge or selvage of the carpet shall be inserted into the loop A E D by first raising the arm D and then passing the edge of the carpet into the loop. 40

The arms A and D are lengthened to per- mit of a wider or narrower carpet being laid upon the stair without the necessity of al- tering the position of the securer.

What I claim as my invention, and desire 45 to secure by Letters Patent, is—

The combination in a stair-carpet securer made of a single piece of wire formed of a base with open coils for the screws to secure to the step, and with a cone-shaped coil ex- 50 tending at a right angle to the base, all as and for the purposes set forth.

In testimony that I claim the above as my improvements in carpet-fasteners I hereunto set my hand this 1st day of June, 1896.

MINERVA ELIZABETH HALL.
